UNITED STATES PATENT OFFICE.

MARTIN F. KETTLER, OF HOUSTON, TEXAS, ASSIGNOR TO DOWNING PNEUMATIC WHEEL COMPANY, OF HOUSTON, TEXAS.

DESIGN FOR AN AUTOMOBILE WHEEL-RIM.

45,810.

Specification for Design.

Patented May 19, 1914.

Application filed March 28, 1914. Serial No. 828,080. Term of patent 14 years.

To all whom it may concern:

Be it known that I, MARTIN F. KETTLER, a citizen of the United States, residing at Houston, in the county of Harris and State of Texas, have invented a new, original, and ornamental Design for an Automobile Wheel-Rim, of which the following is a specification, reference being had to the accompanying drawing, forming part thereof. Figure 1 is a face view of an automobile

wheel rim showing my new design. Fig. 2 is a sectional view thereof.

I claim—

The ornamental design for automobile wheel rim, as shown.

MARTIN F. KETTLER. [L.S.]
